Patented Nov. 24, 1959

186,722

AUTOMOBILE TAIL LAMP UNIT

John C. Gempel, East Detroit, Mich., assignor to Chrysler Corporation, Highland Park, Mich., a corporation of Delaware

Application June 26, 1959, Serial No. 56,565

Term of patent 7 years

(Cl. D48—32)

FIG. 1

FIG. 2

Des. 186,722

PAGE 2

FIG. 4

Fig. 1 is a side elevational view of an automobile tail lamp unit showing my new design;

Fig. 2 is a top plan view thereof;

Fig. 3 is a side elevational view of the side opposite to that illustrated in Fig. 1; and

Fig. 4 is a front elevational view thereof.

I claim:

The ornamental design for an automobile tail lamp unit, substantially as shown.
